UNITED STATES PATENT OFFICE

2,374,443

ROTARY TABLE MOUNTING FOR
VEGETABLE PEELEERS

Murry G. McClung, Los Angeles, Calif.

Application September 21, 1942, Serial No. 459,210

4 Claims. (Cl. 308—187)

This invention relates to a vegetable peeler of the type set forth in United States Letters Patent No. 2,231,543 issued February 11, 1941, embodying an upstanding cylindrical container fitted with a rotary table, and more particularly pertains to improvements in the mounting of the rotary table and its driving mechanism. The subject matter hereof is shown at least in part in my companion application Serial Number 459,209 which has resulted in Patent No. 2,339,936 issued January 25, 1944.

An object of the invention is to provide a mounting for the rotary table including a support for a rotary shaft on which the table is mounted extending through the bottom wall of the container embodying a construction whereby leakage of water from the container around and through the mounting will be effectively prevented; it being highly desirable to prevent the water used in the peeling operation and which becomes fouled with dirt and peelings from working into the shaft bearings and from leaking onto the shaft driving transmission which is located beneath the container bottom wall.

Another object is to provide a construction whereby the assemblage of the mounting on the container and its association with the bottom wall thereof will be facilitated.

A further object is to provide a construction in the mounting whereby the bearing parts thereof are rendered easily accessible for removal and replacement and whereby wearing parts may be readily renewed so that the mechanism of the peeler may be economically maintained in order.

With the foregoing objects in view, together with such other objects and advantages as may subsequently appear, the invention resides in the parts and in the combination, construction and arrangement of parts hereinafter described and claimed, and illustrated by way of example in the accompanying drawings in which:

Fig. 1 is a view in vertical section, partly in elevation, of the vegetable peeler showing the invention as applied;

Fig. 2 is a horizontal section and plan view taken on the line 2—2 of Fig. 1 with portions broken away;

Fig. 3 is a detail in vertical section taken on the line 3—3 of Fig. 2 with parts shown in elevation;

Fig. 4 is a detail in section and elevation depicting the manner of initially positioning the mounting for the table bearing through the bottom wall of the container;

Fig. 5 is a view in section and elevation similar

to Fig. 4 showing the manner of sealing the joint between the bearing mounting and the container bottom wall;

Fig. 6 is a view in side elevation of the vegetable peeler to which the invention is applied.

Referring to the drawings more specifically, A indicates generally an upright cylindrical container which is open at its ends and is fitted with a removable cover B which loosely seats on the upper end of the container and has a downwardly inclined central portion 7 leading to an opening 8 and which cover serves as a hopper through which articles to be peeled may be directed into the container.

15 Spaced upwardly from the lower open end of the container is an inclined bottom wall 9 from the lower portion of which leads a discharge spout 10 for carrying off wash water which is delivered to the container. Arranged in the container is 20 a horizontally extending rotary table C carried on the upper end of a vertical shaft 11 which extends through a bearing housing D projecting through the bottom wall 9 and which member is carried on a spider E located beneath the bottom wall 9.

25 The legs 12 of the spider have flanges 13 on and formed integral with the hub of their outer ends which abut and are secured to the inner periphery of the wall of the container apart from the bottom wall 9 of the latter. The bearing housing 30 D embodies an upstanding cylindrical portion 14 formed with a circumferential channel 15 providing the bearing supporting member with an intermediate portion 16 of reduced diameter. The bottom wall 9 is formed with an opening 17 bordered by an upstanding flange 18 through which the reduced intermediate portion 16 of the bearing supporting member 14 extends. In initially 35 assembling the bearing supporting member in relation to the bottom wall 9, it is inserted through the opening 17 and positioned as shown in Fig. 4 with a packing material 19 interposed between the flange 18 and the reduced portion 16 of the cylinder 14. The upper end of the flange 18 is then beaded inwardly over the packing material

40 45 19 as shown at 20 in Fig. 5. A split clamping ring 21 is then positioned around the flange 18 and is brought into tight encircling engagement therewith by means of a conventional stove bolt 22 and its associated nut 23 engaging the usual ears 24 50 on the ends of the split ring as shown in Fig. 2. A ring 25 of plastic metal compound is then built up between the inturned margin 20 of the flange 18 and the shoulder 26 at the upper margin of the channel 15. A similar ring 27 of plastic metal compound is then built up between the lower mar-

55

gin of the opening 17 to extend around the lower portion of the reduced portion 16 of the bearing housing D between the packing 19 and the shoulder 28 at the lower margin of the channel 15. In this fashion an effective leak-proof seal is afforded between the bearing housing D and the bottom wall 9.

The shaft 11 is formed with a shoulder 29 intermediate the ends thereof which seats on a ball bearing 30 mounted in the housing D on which the shaft is revolubly supported. The bearing 30 comprises the conventional pair of annular raceways *a* and *b* with balls *c* interposed therebetween. The inner portion of the upper annulus *a* underlies the shoulder 29 while the outer portion thereof underlies the lower end of the bushing 31 in spaced relation thereto to provide a space 37 around the shaft 11 immediately above the bearing 30. The upper portion of the shaft 11 is encompassed by an elongated wearing bushing 31 fitted in the upper portion of the bearing housing D and projecting slightly above the upper end of the latter. A flange 32 on the upper end portion of the shaft 11 overlies the upper end of the bushing 31 in close proximity thereto but spaced therefrom and carried thereon is a disk 33 having a downturned marginal apron 34 overlying the margin of the flange 32 and the upper end portion of the bushing 31 so as to span and seal the gap between the end of the bushing 31 and the flange 32. The upper end of the shaft 11 is formed with a threaded stud 35 for screw engagement with the rotary table C; the latter being formed on its underside with a threaded socket 36 for reception of the stud 35. The screw threads of the stud 35 and socket 36 are spiralled in a direction opposite to the direction of normal operative rotation of the shaft 11 so that rotation of the shaft in its forward direction will tend to tighten the stud in the socket.

The space 37 is provided around the shaft 11 at the lower end of the bushing 31 and just above the bearing 30 for reception of a packing and lubricating grease which is delivered to this space and to spaces in the bearing communicating therewith through a lubricant supply tube 38 connecting with a passage 39 leading through the bearing housing D to the space 37. The grease receiving space 37 and passage 39 are located below the bottom wall 9 of the container whereby the grease may be applied when need be from the exterior of the container.

The lower end portion of the shaft 11 extends through a wearing bushing 40 removably housed in a sleeve 41 seated in the lower end of the bearing housing D, which lower end of the shaft has removably fixed thereon a pulley wheel 42, the hub 43 of which forms an abutment for the lower end of the bushing 40 which projects through an opening 44 in the lower end of the bearing housing. The sleeve 41 seats on a flange 45 forming the margin of the opening 44. The upper ends of the bushing 40 and sleeve 41 terminate on a plane spaced a short distance above the lower end of the housing and remote from the upper end of the latter; and form a seat for the lower raceway *b* of the ball bearing 30 and whereby the ball bearing is positioned close to but above the lower end of the housing contiguous the spider E. The wheel 42 is engaged by a belt 46 passing around the drive wheel 47 of an electric motor 48 mounted on the container A; the latter being fitted with a face plate 49 carrying threaded studs 50 which extend through side flanges 51 of the motor 48 and are

engaged by nuts 52 to effect fastening of the motor on the housing.

Affixed by screws 53 to the underside of the spider E is a transmission guard F embodying a top plate 54 which overlies the wheels 42 and 47 and their associated belt 46; the top plate being formed with an opening *d* through which the shaft 11 extends and with an opening *e* through which the shaft of the motor 48 extends. A protective apron 55 depends from the margin of the top plate 54 which is arranged to lie close to but spaced from the belt 46 throughout the length thereof.

By the construction set forth, assemblage of the rotary table C and its mounting may be readily accomplished. To effect mounting of the rotary table the shaft 11 is initially attached thereto by screwing the threaded end stud 35 thereof into engagement with the correspondingly threaded recess 36 on the underside of the table with the flange 32 on the shaft abutting the disk 33 to hold the latter in place. The assembled bushing 40 and sleeve 41 are then positioned in the bearing housing whereupon the ball bearing 30 is seated on the bushing and sleeve. The bushing 31 is then set in place in the bearing housing with a tight fit. The shaft 13 carrying the table 12 is then put in place by inserting the shaft through the bushings 31 and 40 to seat the shoulder 29 of the shaft on the upper and free raceway *a* of the bearing 30. The pulley wheel 42 is then attached to the lower end of the shaft 11 in a conventional fashion as by a key 56 and set screw 57. When thus assembled the shaft 11 will be supported intermediate its ends on a foot ball bearing and will be retained in its upright position by the bushings 31 and 40 disposed on opposite sides of the ball bearing. By this arrangement the point of greatest wear in the bearing structure will be in the bushings 31 and 40 which may be easily removed and replaced.

By forming the seal between the bearing housing and the container bottom wall as set forth, leakage from the container at this point will be prevented, and by the provisions of the clamping ring 21 the flange 18 will be reinforced and tightly held against outward distortion such as to loosen the packing and whereby the seal is rendered highly durable.

By packing the bearing with a heavy grease and providing the protective apron 34 at the upper end of the upper bushing 31, leakage of water through the bearing will be effectively prevented.

While I have shown and described a specific embodiment of my invention I do not limit myself to the exact details of construction set forth, and the invention embraces such changes, modifications and equivalents of the parts and their formation and arrangement as come within the purview of the appended claims.

I claim:

1. A rotary table mounting for vegetable peelers, an upstanding open ended tubular bearing housing formed with an inturned flange at its lower end, a sleeve in said housing seating on said flange, a wearing bushing carried by said sleeve, a ball-bearing assembly seating on said sleeve, a revoluble table supporting shaft extending through said housing seating on said bearing assembly and having its lower end portion projecting through and guided in said bushing, an elongated wearing bushing in the upper portion of said housing encompassing and guiding the upper portion of said shaft; said ball-bearing assembly being located adjacent to the lower end

of said housing and remote from the upper end thereof, and means for directing lubricating and packing grease around said shaft above and contiguous to said ball bearing assembly.

2. A rotary table mounting for vegetable peelers having a container provided with a bottom wall, an upstanding open ended tubular bearing housing extending through and projecting above and below said wall, an inwardly extending flange on the lower portion of said housing, a sleeve in said housing seating on said flange, a bushing in said sleeve, a ball bearing assembly at the upper end of said sleeve and bushing, a revoluble table supporting shaft extending downwardly through said housing having an enlarged upper end portion and a reduced lower end portion with a shoulder at the juncture of said end portions seating on the inner marginal portion of said ball-bearing assembly, the reduced lower end portion of said shaft extending through and guided in said bushing, and an elongated wearing bushing interposed between the enlarged upper end of said shaft and said housing having its lower end contiguous to but spaced from the outer marginal portion of said ball-bearing assembly to form a space for the reception of packing and lubricating grease, said housing having a grease supply passage therethrough leading to said space; said passage and space being located below the container bottom wall.

3. In a vegetable peeler, a vertically extending cylindrical container having a bottom wall, a bearing housing projecting upwardly through the central part of said bottom wall; means underlying said container supporting said bearing housing, a driving shaft extending from a point below said container upwardly into the central portion thereof through said housing, said shaft having a diametrically enlarged portion interiorly of said housing thereby producing around it a downwardly facing angular shoulder within said hous-

ing, there being an annular space between said enlarged shaft portion and said bearing housing, a ball bearing surrounding such shaft below said shoulder and having an annulus underlying the latter supporting said shaft, said bearing being located below the bottom of said container, supporting means for said bearing within said housing, the outer peripheral portion of said annulus projecting outwardly beyond said shoulder portion of said shaft, a bushing above said bearing fitted into the said annular space between said bearing housing and the diametrically enlarged portion of said shaft, said bushing being maintained with its lower end in a vertically spaced 10 superjacent relation to said bearing annulus; and means including a pipe leading below said container bottom to conduct a lubricant through the wall of said bearing housing into the space between said bearing annulus and the lower end 15 of said bushing.

4. In a rotary table mounting for vegetable peelers having an upright cylindrical container provided with a bottom wall and with a bearing supporting spider beneath said wall; an upstanding open ended tubular bearing housing formed integral with the hub of said spider having an inturned flange on its lower end and having its upper end projecting through and fastened to said bottom wall, a sleeve in said housing supported on said flange, a bushing in said sleeve, a ball bearing assembly supported on said sleeve located contiguous said spider, a bushing extending into the upper end of said housing having its lower end terminating contiguous said bearing assembly, and a table supporting shaft extending through said housing having a shoulder intermediate its ends seating on said bearing with the end portions of the shaft extending through and guided in said bushings.
